UNITED STATES PATENT OFFICE.

ELLA O'DONNELL AND BEATRICE PINTOFF, OF NEW YORK, N. Y., ASSIGNEES TO ISAAC GINSBERG & BROS., OF NEW YORK, N. Y.

EXTENSIBLE GARMENT.

Application filed October 11, 1922. Serial No. 593,862.

To all whom it may concern:

Be it known that we, ELLA O'DONNELL, a citizen of the United States, and BEATRICE PINTOFF, a citizen of Russia, both residing at New York, in the county and State of New York, have invented certain new and useful Improvements in Extensible Garments, of which the following is a specification.

10 This invention relates to garments such as dresses, robes or wrappers, but more especially those in which the waist and skirt portions are continuous one with the other.

15 It is the object of the invention to improve the garments so that the general shape thereof may be retained even though the size is increased at the waist portion.

20 Another object of the invention is to provide a garment which is adjustable as to size so that the same is readily adapted to fit persons of different sizes or a person undergoing physiological development and is especially valuable as a maternity dress.

25 Another object of the invention is to provide a garment that will be comparatively free or wrinkles in its front or back and to locate any wrinkles in the side of the garment where they will be least noticeable, keeping the front and back of the garment 30 ordinarily free of wrinkles, even if the garment is worn by people of different waist development.

With these objects in view and others which will appear to those skilled in the 35 garment producing art as this description proceeds, the invention will be described in connection with the accompanying drawings of which:

40 Figure 1 is a representation of the front of a garment.

Fig. 2 is a representation of the side of the garment with the sleeves removed showing the appearance of the body of the garment on, say, a normally shaped individual.

45 Fig. 3 is a side view showing the appearance of the same garment on a larger sized person.

50 Referring to the details of the drawings in which like numerals are used to designate the same parts in all the views, 1 indicates the front of the garment. This may be cut to fit various fullnesses in the bust or front of the person for whom the garment is designed. It is desirable that the front of the 55 garment should appear smooth and without

wrinkles and the front, therefore is intended to fit the outlines of the person wearing the garment snugly and since in the preferred form there are no wrinkles or pleats in the front of the garment it will present a neat 60 appearance.

Just below the arm holes 2 a part of the material of the garment is cut away and there is inserted a pleated piece of material 3 with the outer folds of the pleats sewed 65 in at 4. These pleats run from the bottom to the top of the extra piece 3 which is sewed in to the front and back portions 1 and 5 by seams running across the top of the piece 3 and from the bottom to the top 70 on both sides of the pleated piece. The intervening edges of the pleats are not sewed but are left free to expand.

The back 5 like the front 1 is preferably plain and unpleated but, cut to fit the form 75 more or less snugly and because of the garment wrinkling or creasing only in the inserted piece 3 which is constructed to normally assume a pleated condition, the back as well as the front will in its preferred 80 form normally be kept clear of wrinkles and creases, and furthermore since the pleated inserted portions 3 may be easily extended horizontally the garment can be easily changed from the shape shown in Figure 2 85 to the shape shown in Fig. 3.

The garment may have at the waist a belt 6 which is made long enough to extend around different sized wearers, and in front it may have pockets 7 and a collar 8. The 90 sleeves 9 are of the construction shown and the length of the garment may be varied to suit the taste of the wearer.

The front and back portions of the garment may in some instances be made of a 95 single piece of cloth with cut out portions to make it fit the form of the wearer.

Having described the invention what we claim as new is:

1. A dress, for house or street wear composed entirely of front and back portions, extending from the shoulders the full length of the dress, the dress having cut out portions extending at its top a short horizontal distance just below the arm, and thence 105 downwardly to the bottom of the dress, and a piece having a horizontal top end inserted in the cut out portion, said piece being creased or pleated at the top horizontal end and each crease or pleat extending from the 110

top horizontal end to the bottom of the dress, said pleated portion being sewed into the cut out portion by a seam extending along the horizontal top of the inserted piece and on either side of the inserted portion from its bottom to its top. 5

2. A dress for street or house wear adapted to fit persons of various sizes composed entirely of front and back portions, both 10 said portions extending from the shoulders downwardly the full length of the dress, said dress having a cut out portion extending horizontally from front to rear, thence downwardly from near the arm pit to the 15 bottom of the dress, a piece to fill in the cut out portion, said piece being pleated from the horizontal top of the cut out portion, to the bottom of the dress, the pleated portion being sewed into the dress across 20 the horizontal portion and down the sides of the cut out portion, all the ends of the pleats terminating in the horizontal portion, thus allowing the dress to neatly fit

persons of different sizes, while retaining a 25 neat appearance.

3. A street dress composed entirely of front and back portions in one piece, said front and back portions at their meeting edges having a cut out portion extending horizontally from the front to rear and then 30 downwardly from near both arms to the bottom of the garment, the cut out portion being filled in with pleated portions sewed into the one piece portion at the top horizontal end of the cut out portion and along 35 its sides to the bottom of the dress, all the pleats in the pleated portion extending from the horizontal top of the pleated portion downwardly to the bottom of the dress, the ends of the pleats being all just beneath the 40 arm pit.

In testimony whereof we hereunto affix our signatures.

ELLA O'DONNELL.
BEATRICE PINTOFF.
